UNITED STATES PATENT OFFICE.

EDWIN S. LENOX, OF WORCESTER, MASSACHUSETTS.

FENCE-WIRE FASTENING.

SPECIFICATION forming part of Letters Patent No. 295,565, dated March 25, 1884.

Application filed June 4, 1883. (No model.)

To all whom it may concern:

Be it known that I, EDWIN S. LENOX, of Worcester, in the State of Massachusetts, have invented an Improvement in Fence-Wire Fastenings, of which the following is a specification.

This fastening is adapted to receive and hold a fence-wire in which there are one or more strands. It is usual to employ staples driven into the post and confining the wire against the same. It is the practice to drive the staple in with sufficient force to produce a bend in the wire against the post to prevent the wire slipping endwise; but the concussion and the sudden bend is liable to injure the metal of the wire and cause it to crack. By my improvement the wire receives only a small lateral bend to prevent end motion, and there is no violent nipping or injurious action upon the wire, and said wire cannot be removed from the fastening when drawn tight, but it can be lifted out of the fastening when the wire is slackened without having to remove or loosen the fastening from the post. This is a great convenience in repairing broken fence-wires.

In the drawings, Figure 1 is a plan view of the fastening. Fig. 2 is a side view, and Fig. 3 is a front view.

The spike portion *a* of the fastening is adapted to be driven into the post. It usually will have notched or serrated edges or sides. The head *b* of the spike is provided with projecting studs *c d*—usually two—and they are placed and inclined in opposite directions, as shown, in order that they may catch in opposite directions over the fence-wire *f*. This fence-wire is either one or more strands, and when the fastening is hooked upon the wire the spike portion is at less than a right angle to

the wire, as indicated by dotted lines; hence when the spike is driven the wire will be slightly bent, as shown, so as to confine it and prevent end motion to the wire through the fastening. This will be easily accomplished by a little dexterity in driving the staple, because if the hammer is struck in the direction indicated by the arrow, Fig. 1, instead of exactly in line with the spike, the spike will be pressed into the proper position to the fence-wire to bend and confine the same in the act of driving.

If desired, the studs may be sufficiently far apart transversely to the wire to allow the wire to slip endwise through the fastening. In this case the wire is kept in position laterally and supported.

It is not necessary to drive the spike until the side of the wire comes into contact with the post; and by allowing the fastening to occupy the position to the post indicated in the drawings the wire can be lifted out if it is slackened up sufficiently, but not otherwise.

I claim as my invention—

The fastening for fence-wire having a spike portion to be driven into the post, the studs *c d* on the side of the head portion, and inclined in opposite directions and at a sufficient distance apart longitudinally of the wire to allow such wire to be introduced between the studs when at an inclination to the fastening, substantially as set forth.

Signed by me this 25th day of May, A. D. 1883.

EDWIN S. LENOX.
